UNITED STATES PATENT OFFICE.

FRANCES W. DAVIS, OF COLORADO SPRINGS, COLORADO.

ADJUSTABLE BED-TABLE.

1,118,746.

Specification of Letters Patent.

Patented Nov. 24, 1914.

Application filed July 10, 1913. Serial No. 778,319.

To all whom it may concern:

Be it known that I, FRANCES W. DAVIS, a citizen of the United States, residing at Colorado Springs, in the county of El Paso,

5 State of Colorado, have invented certain new and useful Improvements in Adjustable Bed-Tables; and I do hereby declare the following to be a full, clear, and exact description of the invention, such as will 10 enable others skilled in the art to which it appertains to make and use the same.

This invention relates to tables for attachment to beds and has for an object to provide a table which may be swung over the 15 bed and adjusted vertically to be within convenient reach of the patient, or may be dropped and swung under the bed to be out of the way when not in use.

A further object of the invention is to 20 provide an extremely simple table of this character which is formed of a few parts that may be constructed at a minimum expense and will not easily get out of order.

With the above objects in view the invention 25 consists of certain novel details of construction and combination of parts herein-after fully described and claimed, it being understood that various modifications may be made in the minor details of construction 30 within the scope of the appended claim.

In the accompanying drawing illustrating 35 this invention: Figure 1 is a front elevation showing the table attached to a bed and with the parts of the table in swung outward position. Fig. 2 is a plan view showing the parts of the table in position above the bed. Fig. 3 is a cross sectional view on the line 3—3 Fig. 1. Fig. 4 is a cross sectional view on the line 4—4 Fig. 1.

40 Referring now to the drawing in which like characters of reference designate similar parts, 10 designates one of the posts of the head of a bed 11.

In carrying out my invention I provide a 45 rod 12 which extends vertically along the post 10 and is equipped at the ends with right angular extensions 13 that carry clamps 14 which are adjustably secured by means of set screws 15 to any desired position vertically on the post 10. A rod 16 is provided

at one end with a sleeve 17 which is adjustably secured on the rod 12 by means of a set screw 18. The rod 16 is equipped at the free end with a head 19.

The table 20 is formed of any desired material and is provided with a raised edge 21 to prevent the articles from sliding off from the table. An arm 22 is secured to the center of one longitudinal edge of the table and is equipped with a sleeve 23 that is adjustably secured to the rod 16 by means of a set screw 24. It is now evident that by loosening the set screw 18 the rod 16 may be swung on the rod 12 as a vertical pivot and may be also raised or lowered on the rod 12. Also 65 that by loosening the set screw 24 the table 20 may be rocked upon the rod 16 as a horizontal pivot and may be also slid longitudinally of the rod 16.

In use the table 20 is rocked outwardly to 70 a horizontal plane and then the rod 16 is rocked inwardly over the bed, the set screw 18 being then tightened to hold the table in operative position, it being understood that before the set screw is tightened that the 75 table is adjusted vertically to suit the convenience of the patient. When not in use the rod 16 may be rocked outwardly against the wall of a room and the table 20 rocked downwardly against the wall, the parts 80 being shown in this position in Fig. 1. Or if desired, the rod 16 may be lowered and rocked underneath the bed to dispose the table entirely out of the way.

From the above description it will be seen 85 that I have provided an extremely simple device of the class described which may be formed from a few inexpensive parts that are strong and durable and will not easily get out of order.

What is claimed, is:

The combination with a bed provided with a post and a side rail; of a bracket adjustably attached to said post above said side rail, a second bracket attached to said post 95 below said side rail, a bar extending parallel to said post and attached to said brackets, a sleeve slidably and rotatably mounted on said bar, means to lock said sleeve in adjusted position on said bar, a bar extending 100

from said sleeve radially of the first mentioned bar, a second sleeve slidably and rotatably mounted on the second bar, means to lock said second sleeve in adjusted position on said second bar, a bar attached to the second sleeve and extending radially from the second bar, and a table supported on the last mentioned bar.

In testimony whereof, I affix my signature, in the presence of two witnesses.

FRANCES W. DAVIS.
